UNITED STATES PATENT OFFICE.

JEAN BAPTISTE GUSTAVE ADOLPHE CANET, OF PARIS, FRANCE, ASSIGNOR OF ONE-HALF TO SIR JOSEPH WHITWORTH & COMPANY, LIMITED, OF OPENSHAW, ENGLAND.

RECOIL-CHECK FOR DISAPPEARING-GUN CARRIAGES.

SPECIFICATION forming part of Letters Patent No. 447,227, dated February 24, 1891.

Application filed December 31, 1888. Serial No. 295,052. (No model.) Patented in England November 12, 1887, No. 15,514, and November 14, 1887, No. 15,592, and in France January 28, 1888, No. 188,413.

To all whom it may concern:

Be it known that I, JEAN BAPTISTE GUSTAVE ADOLPHE CANET, civil engineer, a citizen of the Republic of France, and resident 5 of Paris, France, have invented new and useful Improvements in and Relating to Gun Carriages or Mountings, (for which I have obtained patents in Great Britain, No. 15,514, bearing date November 12, 1887, and No. 10 15,592, bearing date November 14, 1887, and in France, No. 188,413, bearing date January 28, 1888,) of which the following is a specification, reference being had to the accompanying drawings.

15 This invention relates to gun carriages or mountings wherein the gun is supported by a rocking lever, which when the gun recoils turns upon or about its fulcrum or pivot, and thus allows the gun to retire or disappear be- 20 hind or below a wall or parapet at or immediately after the moment of firing.

The chief feature of the said invention is the employment of a rotary or oscillatory hydraulic brake in combination with the said 25 rocking lever, as hereinafter set forth.

The said invention moreover comprises other improvements hereinafter described.

In the accompanying drawings I have shown how my said invention may be conveniently 30 and advantageously carried into practice.

Figure 1 is a plan of the improved gun-mounting, showing the parts in the recoiled position. Fig. 1^a is a vertical section on the line *y y*, Fig. 1. Fig. 2 is a vertical longitudinal central section, showing the parts in full lines in the firing position and in dotted lines in the recoiled position, the extreme angles of elevation and depression being indicated by the dotted lines *y y* and *z z*. Fig. 3 is a 35 rear elevation, partly in transverse section on the line *x x*, Fig. 1. Fig. 3^a is a vertical section, on an enlarged scale, of the controlling and by-pass valves. Fig. 4 is a section on the line *x' x'*, Fig. 2, illustrating details 40 of construction. Fig. 5 is a sectional elevation illustrating an arrangement of training-gear hereinafter described.

A is a base-plate or racer, forming also a center pivot.

45 B is a rotating platform or turn-table, which

is supported upon the said base-plate or racer through the medium of rollers A', and is provided with one or more clips B' to prevent tilting of the gun and mounting.

C is the rocking lever, in the upper end of 55 which the gun is held by means of its trunnions.

D is a hollow cylinder, which is formed with or rigidly attached to the rocking lever C, so that it serves as the boss thereof and is 60 movable therewith. This cylinder is fitted to turn or oscillate upon a fixed inner cylinder or drum E, provided at its ends with hollow trunnions or projections E', whereby it is securely held in brackets or cheeks B², 65 extending upward from the platform or turn-table B. This inner cylinder or drum serves as a fixed axle or fulcrum around which the said lever turns.

The outer cylinder D is provided with a 70 segment d, projecting from its interior surface and extending throughout the half or nearly the half of its circumference, and this segment is in contact with the exterior surface of the inner cylinder or drum E. The 75 said inner cylinder or drum E is provided with a segment e, projecting from its outer surface and extending around it for about one-fourth of its circumference. This segment e is in contact with the interior surface 80 of the cylinder D. There is therefore a clear space f between the two cylinders throughout the remainder of the circumference thereof. The cylinder D has part of its inner surface eccentric to the segment e, as at d'. The said cylinder D is furnished with side or end pieces or covers D', which are firmly bolted or otherwise secured thereto, and which encircle the trunnions or projections E' of the inner cylinder or drum E. The inner cylinder 85 E is formed with passages e', affording communication between the space f and a central chamber or space g in the said cylinder E. The said chamber or space g communicates with recuperator apparatus through 90 the hollow trunnions E' and through pipes h, provided with loaded or non-return valves j. This recuperator apparatus comprises hydraulic presses k, the rams or plungers k' of 95 which are formed with or attached to the rams 100

or plungers l' of air-cylinders l , which are firmly secured by bolts b to the turn-table B. A suitable by-pass valve j' is arranged in combination with each of the valves j to permit 5 the return of the liquid from the hydraulic presses k into the space f for the purpose of raising the gun to the firing position. The air-cylinders l are connected by pipes m' with a chamber or reservoir m , which rotates with 10 the mounting and serves to equalize the pressure in the air-cylinders. A suitable pump is in some instances connected with the reservoir m to compress the air in the said reservoir, and thus obtain an initial pressure 15 therein and in the said air-cylinders or compensate for loss of pressure therein.

It will be seen that by means of my rotary or oscillating apparatus I apply the brake-power directly to the lever at the axis of the 20 same without the intervention of levers and rods or links for connecting the lever to the brake, thus simplifying the construction. When the gun recoils, the lever C and the cylinder D turn upon or about the trunnions 25 or projections E' of the inner cylinder or drum E. In this movement of the said lever and cylinder the segmental projection d acts as a piston or plunger to drive or force out the liquid contained in the space f . This liquid 30 can only escape through a narrow space between the segment e and the eccentric portion d' of the cylinder D, which space continually varies during the movement of the said cylinder by reason of the eccentric formation of 35 the said part d' thereof in such a manner as to gradually increase the resistance to the passage or escape of the liquid. The liquid is forced through the passages e' in the cylinder or drum E and through the hollow trunnions or projections E', and, opening the 40 valves j , passes through the pipes h into the presses k , and by its action upon the rams or plungers k' compresses the air in the cylinders l and chamber or reservoir m . The return 45 of the gun to the firing position will be effected by the reaction or expansion of the air thus compressed, when the by-pass valves are opened to permit the liquid to flow under the pressure of the air from the said hydraulic 50 presses into the hydraulic brake.

The joints or working-surfaces of the apparatus are suitably packed where necessary to make them fluid-tight.

The air-cylinders and the liquid-cylinders 55 are preferably made distinct or separate from one another. They are placed as shown or in any other suitable position.

The gun-mounting is provided with parallel-motion apparatus—that is to say, with apparatus 60 for keeping the gun parallel to the line of fire in its recoil and in its return movement while permitting its adjustment for vertical pointing or elevation. I prefer to employ for this purpose the apparatus shown in 65 the drawings. This apparatus comprises arms or levers O, loosely mounted upon the trunnions or projections E' of the inner cylinder

or drum E. The said arms or levers are connected to the gun by rods or links P, and are provided with toothed segments O', which are 70 geared with pinions Q, fixed on a shaft Q'. A worm-wheel R, arranged upon this shaft, is geared with a worm R' provided with a hand-wheel R² for rotating it, and is connected with the shaft Q' by means of the well-known device of friction cones or clutches. By turning the hand-wheel R² the worm-wheel R may be operated to impart motion to the shaft Q' and pinions Q through the medium of the friction-cones, and the vertical pointing or elevation of the gun or movement of the same about its trunnions will be thereby effected. The arms O and rods P, arranged in combination with the gun and the rocking-lever C, as above described, form a jointed 85 parallelogram, whereby the gun in its recoil, unless subjected to abnormal or excessively severe stresses, is kept parallel to the line of fire, and by making the vertical angle of the gun dependent upon the position of and controllable through the arms O, I am enabled to effect the elevation or depression without impairing or changing the action of the parallelogram in respect of preventing deviation 90 of the gun from the line of fire in its recoil 95 or in its return to the firing position. Moreover the elevating mechanism is behind or below the wall or parapet. Therefore the elevation or depression of the gun can be effected without exposure of the gunners to an enemy's 100 fire.

To provide for training the gun by hand a circular rack n is formed or fixed on the base-plate A, and has geared therewith a pinion o , fixed on the lower end of a vertical shaft o' , 105 on the upper end of which is fixed a worm-wheel p . This worm-wheel has geared therewith a worm q , which is provided with cranks or handles q' .

For training the gun by hydraulic or other power I sometimes employ the gearing shown 110 in Fig. 5, wherein an internally-toothed rack n' is fixed or formed upon the turn-table B, and has geared therewith a pinion r , fixed upon a vertical shaft r' , supported in bearings 115 formed with or firmly attached to the base-plate A, or other stationary support. On the said shaft r' is also fixed a bevel-wheel s , geared with another bevel-wheel s' , fixed on a horizontal shaft t , to which rotary motion 120 is imparted by hydraulic or other power. I do not, however, confine myself to the use of any special form of elevating or training gear, or of apparatus for keeping the gun parallel, as above described. Moreover my invention 125 is applicable to gun-mountings wherein no provision is made for keeping the gun parallel to the line of fire during its recoil or during its return to the firing position.

The construction of my apparatus can be 130 somewhat further modified without departing from the nature of my said invention. For example, springs or other recuperator apparatus may be substituted for the air-com-

pressors above described, for effecting the return of the gun to the firing position; or the recuperators may be dispensed with, the discharge of the liquid from the recoil-brake taking place into a tank, and the gun being returned to the firing position by the pressure of water from a pump or accumulator. The construction of the oscillating hydraulic brake is in some cases modified by having the outer cylinder rigidly attached to the turn-table or frame, and the inner cylinder or drum formed on or attached to the rocking lever.

What I claim is—

1. The combination, with a rocking lever for carrying a gun, of a rotary or oscillatory hydraulic apparatus comprising an outer cylinder and an inner cylinder or drum, one of which is fixed and the other of which is capable of rotation or oscillation about its axis and is firmly attached to the said lever, for the purposes above specified.

2. The combination, with a rocking lever for carrying a gun, of the rotary or oscillatory hydraulic apparatus, the outer cylinder of which is firmly attached to the said lever and the inner cylinder or drum of which serves as the pivot-pin or fulcrum of the said lever, substantially as and for the purposes set forth.

3. The combination, with a rocking lever for carrying a gun, of a rotary or oscillatory hydraulic brake comprising an outer cylinder and an inner cylinder or drum, one of which is fixed and the other of which is capable of rotation or oscillation about its axis and is firmly attached to the said lever, and apparatus which receives the liquid from the said brake in the recoil and descent of the gun and forces the said liquid back into the said brake to effect the return of the gun to the firing position, substantially as and for the purposes above specified.

4. The combination, with a rocking lever for carrying a gun, of a rotary or oscillatory hydraulic brake comprising an outer cylinder and an inner cylinder or drum, one of which is fixed and the other of which is capable of rotation or oscillation about its axis and is firmly attached to the said lever, and a recuperator comprising a cylinder connected with the said brake and provided with a ram or piston and an air-compressor or its equivalent, whereby energy is stored during the recoil and descent of the gun and is utilized for effecting the return of the gun to the firing position, substantially as and for the purposes above specified.

5. The combination, with a rocking lever for carrying a gun, of a rotary or oscillatory hydraulic brake comprising an outer cylinder and an inner cylinder or drum, one of which is fixed and the other of which is capable of rotation or oscillation about its axis and is firmly attached to the said lever, and which are provided with projecting segments forming a piston and abutments, substantially as and for the purposes above specified.

6. The combination, with a rocking lever for carrying a gun, of a rotary or oscillatory hydraulic brake comprising an outer cylinder 70 firmly attached to the said lever and provided with an inwardly-projecting segment or piston, and an inner cylinder or drum secured to the base-plate, turn-table, or platform of the gun-mounting and provided with an outwardly-projecting segment, forming abutments, and with ports or passages for the ingress and egress of the fluid, substantially as and for the purposes above specified.

7. The combination, with a rocking lever 80 for carrying a gun, of a rotary or oscillatory hydraulic brake comprising an outer cylinder and an inner cylinder or drum, one of which is fixed and the other of which is capable of rotation or oscillation about its axis and is 85 firmly attached to the said lever, a recuperator comprising a cylinder connected with the said brake and provided with a ram or piston and an air-compressor which is acted upon by and reacts upon the said ram or piston, and a compressed-air chamber or reservoir in communication with the said compressor, substantially as and for the purposes above specified.

8. The combination, with a rocking lever 95 for carrying a gun, of a rotary or oscillatory hydraulic brake comprising an outer cylinder and an inner cylinder or drum, one of which is fixed and the other of which is capable of rotation or oscillation about its axis and is firmly attached to the said lever, and a parallel-motion apparatus comprising an arm arranged to turn about the axis of the movable cylinder, mechanism for elevating the gun by the adjustment of the said arm, and a rod or link parallel with the rocking lever and 100 coupled at one end to the said arm and at its other end to the gun, substantially as and for the purposes above specified.

9. The combination, with a rocking lever 110 for carrying a gun, of a rotary or oscillatory hydraulic brake comprising an outer cylinder and an inner cylinder or drum, one of which is fixed and the other of which is capable of rotation or oscillation about its axis and is firmly attached to the said lever, and a parallel-motion apparatus comprising an arm arranged to turn about the axis of the movable cylinder, mechanism for elevating the gun by the adjustment of the said arm, and a rod or link parallel with the rocking lever and 115 coupled at one end to the said arm and at its other end to the gun, a recuperator comprising a cylinder connected with the said brake and provided with a ram or piston, and an air-compressor which is acted upon by and reacts upon the said ram or piston, substantially as and for the purposes above specified.

10. In a gun-mounting, the combination of the rocking lever carrying the gun, a hydraulic brake comprising an inner cylinder 130 or drum secured to the turn-table or platform of the gun-mounting, and an outer cylinder firmly attached to and serving as the boss or bearing of the said lever, a parallel-motion ap-

paratus comprising arms or levers provided with toothed segments and loosely mounted on trunnions or projections on the said inner cylinder, and rods or links connecting the 5 said arms or levers to the gun, and elevating mechanism comprising toothed pinionsgeared with the said toothed segments, a worm-wheel connected by friction cones or clutches with the said pinions, and a worm geared with the 10 said worm-wheel and provided with a handle

for rotating it, substantially as and for the purposes set forth.

In testimony whereof I have hereunto signed my name in the presence of two subscribing witnesses.

JEAN BAPTISTE GUSTAVE ADOLPHE CANET.
